Primary Examiner — Derrick Holland(74) *Attorney, Agent, or Firm* — Stetina Brunda Garred & Brucker; Lowell Anderson**CLAIM**

The ornamental design for an engine powered generator, as shown and described.

DESCRIPTION

FIG. 1 is a front, right and top perspective view of an engine powered generator showing our new design;

FIG. 2. is a front elevation view thereof;

FIG. 3 is a right side elevation view thereof;

FIG. 4 is a back, left and top perspective view;

FIG. 5 is a left side elevation view thereof;

FIG. 6 is a back elevation view thereof;

FIG. 7 is a top plan view thereof; and,

FIG. 8 is a bottom plan view thereof.

The broken lines shown represent unclaimed subject matter and form no part of the claimed design.

1 Claim, 8 Drawing Sheets(56)
